MEANS FOR SPRAYING LIQUIDS

Filed Oct. 1, 1927

UNITED STATES PATENT OFFICE

HARRY W. PAGE, OF WAUWATOSA, WISCONSIN

MEANS FOR SPRAYING LIQUIDS

Application filed October 1, 1927. Serial No. 223,477.

In air cleaning processes, the air is blown or drawn through a spray of water. In order to obtain the most efficient results it is desirable that the water be very finely divided and be distributed over a sufficient area to avoid the necessity of causing the air to flow at too high a speed. One form of apparatus that is used for producing a spray consists of a revolving table having along the periphery a fence-like arrangement composed of long pins, the water being discharged upon the center of the table from a nozzle and being thrown outwardly by centrifugal force and being finally broken up by the pins as it leaves the table. There are several objections to this old form of apparatus. Since the table as a whole revolves, the adhesion between the water and the table causes the layer of water next to the table to revolve at the same speed as the latter, so that it simply flows off the edge of the table between the pins and is not broken up. Furthermore, the control of the flow of water to the table is through a valve that cuts down the pressure as the flow is reduced, thus changing the characteristics of the spraying operation.

Viewed in a specific aspect, the present invention may be said to have for its objects to improve the aforesaid apparatus so as to insure that none of the water reaching the pins will be moving angularly with the pins but in a radial direction, so that all of the water will be beaten by the pins and be transformed into a fine spray, and permit the rate of flow of the water to be varied without affecting its radial speed of travel. A further specific object is to permit ready adjustment to be made to vary the line of contact between what may be termed the sheet of water and the pins.

Broadly speaking, the present invention may be said to have for its object to produce a simple and novel mechanism for efficiently transforming a body of liquid into a fine spray.

The various features of novelty whereby my invention is characterized will hereinafter be pointed out with particularity in the claims; but, for a full understanding of

my invention and of its objects and advantages, reference may be had to the following detailed description taken in connection with the accompanying drawing, wherein:

Figure 1 is an elevation of an apparatus or mechanism arranged in accordance with the present invention, a fragment of a supporting and enclosing casing being shown in section; Fig. 2 is a view on an enlarged scale, partly in side elevation and partly in section of the immediate liquid delivering and spraying means; and Fig. 3 is a section taken approximately on line 3—3 of Fig. 2.

Referring to the drawing, 1 represents a vertical nozzle adjustably connected to a delivery pipe 2, conveniently by being screwed into the latter and held in any position of adjustment by means of a locknut 3. Below the nozzle is a cone-shaped table 4 whose central axis is vertical and coincident with the long axis of the nozzle. The table may conveniently be supported from the nozzle as, for example, by means of arms 5 extending upwardly from the periphery thereof to a collar 6 screwed upon the nozzle. A locknut 7 serves to hold the collar in any position into which it may be brought. The apex of the conical table projects into or may be caused to project into the nozzle. By rotating the table, to move it up or down, the effective discharge opening of the nozzle may be varied; the table acting as a valve to reduce or increase the area of the discharge opening. Therefore the rate of flow of water from the nozzle may be varied by increasing or decreasing the size of the outlet for the water, without affecting the pressure.

Surrounding the table is an annular row of pins 8 arranged in the form of a frustum of an inverted cone whose central axis is coincident with that of the table. These pins may be fixed upon a suitable ring or spider 9 mounted on the upper end of a shaft 10 driven by an electric motor 11 or other suitable power device. There is no mechanical connection between the table and the pins or their supports, so that the pins may be revolved about the table while the latter remains stationary.

Assuming that water or other liquid is

flowing out of the nozzle and that the shaft 10 is revolving, it will be seen that the liquid will flow in all directions toward the periphery of the table, leaving the table in a substantially radial direction. The force with which the liquid is discharged is sufficient to carry it into the path of the revolving pins which therefore strike the liquid sharply as the latter attempts to pass between them, and 10 breaks the liquid into a fine spray.

The nozzle and the table may be moved as a unit in the vertical direction so as to raise or lower the table without affecting the rate of flow of liquid from the nozzle; thereby permitting the liquid flowing from the table to strike the pins at different elevations to secure the most effective production and distribution of the spray. Furthermore, because the nozzle and the table may be adjusted as a unit in the vertical direction, a variation in the rate of flow from the nozzle may be brought about without varying the position of the table relatively to the beater.

While I have illustrated and described with particularity only a single preferred form of my invention, I do not desire to be limited to the exact structural details thus illustrated and described; but intend to cover all forms and arrangements which come 30 within the definitions of my invention constituting the appended claims.

I claim:

1. In a liquid spraying mechanism, a stationary conical table, means for discharging water upon the same, an annular beater in the form of a frustum of a cone having its long axis coincident with the corresponding axis of the table surrounding the table, means for rotating said beater, and means adjusting the beater and the table relatively to each other in the direction of length of the central axis of the table.

2. In a liquid spraying mechanism, a stationary table having a conical center and arranged to cause liquid deposited upon said center to flow radially in all directions, a beater movable relatively to the table to break up the liquid flowing from the table into a spray, a nozzle above said conical center of 50 the table, means for adjusting the nozzle relatively to the beater and means for adjusting said nozzle and said table relatively to each other to cause said conical center to act as a valve to control the flow of liquid from 55 the nozzle.

3. In a liquid spraying mechanism, a table arranged to cause liquid discharged on the center to flow radially in all directions, a beater cooperating with the table to break 60 up into a spray liquid flowing from the latter, a nozzle for delivering liquid upon the center of the table, means for moving the nozzle and the table from and toward each other and means on the table for varying the 65 effective size of the nozzle outlet as the table

and nozzle are shifted relatively to each other, and means for adjusting the nozzle in the lengthwise direction.

4. In a liquid spraying mechanism, a vertical nozzle, means for adjusting the nozzle in the lengthwise direction, a table below the nozzle, adjustable means for supporting the table from the nozzle, an element on the table serving as a valve to control the size of the nozzle outlet, a beater surrounding the table, 75 and means for revolving the beater.

In testimony whereof, I sign this specification.

HARRY W. PAGE.
